H. AUMANN

ELECTRIC HEATING AND COOKING APPARATUS

Filed June 6, 1924

Inventor:
Hermann Aumann
By George M. Aumann

UNITED STATES PATENT OFFICE.

HEINRICH AUMANN, OF BERLIN, GERMANY.

ELECTRIC HEATING AND COOKING APPARATUS.

Application filed June 6, 1924. Serial No. 718,302.

To all whom it may concern:

Be it known that I, HEINRICH AUMANN, a citizen of the German Republic, residing at Berlin, Germany, have invented certain new and useful Improvements in Electric Heating and Cooking Apparatus, of which the following is a specification.

The electric heating and cooking apparatus of commonly used construction possess the serious inconvenience that the connecting clamps are mounted on the same base plate as the heating bodies wherefrom results that when the apparatus is being used the joints between clamps and base plate suffer from the strong electric energy. It becomes impossible to loosen a screw which is screwed into the clamp, as is for instance the case when the heating bodies are removably fixed. The screw and the clamps are sometimes jammed so that the shaft of the screw will break off when the screw is being unscrewed.

A further inconvenience is that the heating bodies and the electric connections are easily soiled as the cover of the apparatus is not tight and overboiling liquid can filter between the rings, which are of the same profile as the rings commonly used on kitchen ranges, and drop onto the parts mentioned.

The invention has for its object to avoid these inconveniences by improving the profile of the rings on the top plate of the apparatus so that overboiling liquid flows off without getting at the heating bodies owing to the steps formed by the improved profile of the rings. Contact columns are further fixed on a separate base plate by cementation, the heads of said columns projecting through apertures provided in a plate of refractory material so that the contacts or connection points are cooled by the circulating air against the heat radiating from the heating bodies.

An embodiment of the invention is shown by way of example on the accompanying drawing, in which:—

Fig. 1 shows in elevation an electric heating or cooking apparatus.

Fig. 2 is a longitudinal section of Fig. 1.

Fig. 2^a shows how the contact columns are fixed in the separate base plate.

Fig. 3 is a plan view of Fig. 1 partly broken away.

1 is the wall of the electric heating or cooking apparatus and 2, 3, 4 and 5 are the

concentric rings which form the top plate. In the wall 1 of the apparatus air inlet holes 6 are arranged. The rings 2, 3, 4, 5 have each a downwardly turned flange at the outer edge and an upwardly turned flange at the inner edge. The concentric rings are thus not situated all in the same horizontal plane but form steps as shown in Figs. 1 and 2 so that overboiling liquid, instead of filtering through the joints between the concentric rings, as has been hitherto the case, flows off on the outer stepped surface of the concentric rings without getting into the body of the apparatus. The wall 1 of the apparatus is lined on the inner surface with a layer 8 of heat insulating material. In the body of the apparatus an upper plate 14 of refractory material is fixed which has apertures 7. This plate 14 is covered by a perforated protecting plate 13. The body 1 of the apparatus is mounted on a base plate 10 of refractory material which has holes 11 in which the wall screws 12 at the lower ends of the contact columns 9 are cemented. The heating bodies mounted on the upper ends of the contact columns 9 project into the holes 7 of the insulating top plate 14. The perforated protecting plate 13 is removable and it serves to protect the heads of the contact columns against damage. The air flowing in through the air holes 6 in the wall 1 ascends through the holes 7 so that burning of the contact columns 9 or heating bodies is prevented.

I claim:—

1. An electric heating and cooking apparatus comprising in combination a sheet metal casing having air inlet holes in its side wall, concentric rings forming the top plate of said casing, a downwardly turned flange at the outer edge of the three large rings, an upwardly turned flange at the inner edge of the three large rings and at the outer edge of the centre ring, a base plate of refractory material on which said casing is mounted said base plate having cavities, an upper plate of refractory material in said casing having an equal number of holes as said base plate has cavities, contact columns fixed in the cavities of said base plate, heating bodies on the top end of said contact columns projecting into the holes upon said upper plate of refractory material, and a perforated sheet metal protecting plate between said concentric rings and said upper plate of refractory material.

2. An electric heating and cooking apparatus comprising in combination a sheet metal casing having air inlet holes in its side wall, concentric rings forming the top 5 plate of said casing, a downwardly turned flange at the outer edge of the three large rings, an upwardly turned flange at the inner edge of the three large rings and at the outer edge of the centre ring, a base plate 10 of refractory material on which said casing is mounted said base plate having cavities, an upper plate of refractory material in said casing having an equal number of holes as

said base plate has cavities, contact columns, a wall screw at the lower end of each contact column inserted in one of the cavities of said base plate and cemented in the same, heating bodies on the top end of said contact columns projecting into the holes upon said upper plate of refractory material, and 15 a perforated sheet metal protecting plate between said concentric rings and said upper plate of refractory material.

In testimony whereof I affix my signature.

HEINRICH AUMANN.
